[57] CLAIM

The ornamental design for cooking appliance, as shown and described.

DESCRIPTION

FIG. 1 is a perspective view as seen from the top, front and right side of a cooking appliance showing my new design; FIG. 2 is a top plan view thereof; FIG. 3 is a front elevational view thereof; FIG. 4 is a rear elevational view thereof; FIG. 5 is a right side elevational view thereof; and, FIG. 6 is a left side elevational view thereof. The broken lines in FIGS. 3 through 6 showing the feet are used for illustrative purposes only and form no part of the claimed design.
